UNITED STATES PATENT OFFICE.

HERMAN IHLENBURG, OF PHILADELPHIA, PENNSYLVANIA, ASSIGNOR TO
DAVID WOLFE BRUCE, OF NEW YORK, N. Y.

DESIGN FOR A FONT OF PRINTING-TYPE.

SPECIFICATION forming part of Design No. 13,872, dated April 24, 1883.

Application filed March 23, 1883. Term of patent 14 years.

To all whom it may concern:

Be it known that I, HERMAN IHLENBURG, (assignor to DAVID WOLFE BRUCE,) of Philadelphia, in the county of Philadelphia, Pennsylvania, have invented and produced a new and original Design for a Font of Printing-Types, of which the following is a specification.

The nature of my design is clearly shown in the accompanying typographic impression, to which reference is made; and it consists of a heavy letter the up-and-down portions of which are concaved, as shown, shaded by a light ground-work composed of curved tendril-like ornaments. The terminations of the C, E, F, G, L, S, T, and Z are also concaved upon the right, and in the case of the S, T, and Z upon the right and left hand. The lower termina-

tion of the K, Q, and R upon the right terminates in the heavy dot. In the W the up-and-down portions upon the right and left are higher than or extend above the central portion. In the symbol & the curved line with dot termination upon the left is found.

The character of the design is preserved in the punctuation-marks and numerals and dollar and pound marks.

Having now described my invention, I claim as new—

The design for a font of printing-types, as shown and described.

HERMAN IHLENBURG.

In presence of—

WILLIAM V. H. HICKS,
A. SIDNEY DOANE.
